UNITED STATES PATENT OFFICE.

ALBERT LEW, OF BAKER, OREGON.

TIRE-REMOVER.

1,243,534.

Specification of Letters Patent. Patented Oct. 16, 1917.

Application filed June 3, 1915. Serial No. 31,920.

To all whom it may concern:

Be it known that I, ALBERT LEW, a citizen of the United States, and a resident of Baker, in the county of Baker and State of Oregon, have invented a new and useful Improvement in Tire-Removers, of which the following is a specification.

My invention is an improvement in tire removers, and the invention has for its object to provide mechanism of the character specified, for use with demountable rims for contracting the rim after removal from the wheel to permit the placing of the tire.

In the drawings:

Figure 1 is a front view of the improved remover, with the rim expanded,

Fig. 2 is a similar view with the rim contracted,

Fig. 3 is a side view, and

Fig. 4 is a section on the line 4—4 of Fig. 1, looking in the direction of the arrows adjacent to the line.

The present embodiment of the invention comprises a suitable base composed of plates or blocks 1 and 2, or the like, superposed and connected together in any suitable or desired manner. The holding mechanism for the rim consists of three clamps, the central and one lateral clamp being fixed, while the other lateral clamp is movable toward and from the two first named clamps.

The central clamp is mounted on a rod 3, which has its opposite ends threaded and is provided near one end with a fixed stop 5 in the form of a collar on the rod. The rod is placed through an opening in the base near the top thereof, and is engaged by a nut 6 seated in a counterbore or recess in the rear face of the base.

The stop 5 engages the front face of the base to limit the movement of the rod toward the nut. The rod 3 is braced by a brace 7, having at its upper end a collar 8, which embraces the rod, and the lower end of the brace is offset inwardly toward the base as indicated at 7^a, and is secured thereto by means of a bolt or rivet 9^b.

One of the lateral clamps is mounted on the rod 4^a, which is similar to the rod 3 and mounted in the same manner, and the other lateral clamp is mounted on the rod 4, which is mounted for movement with respect to the clamps on the rods 3 and 4^a.

Each of the clamps comprises coöoperating

clamping members or sections 9 and 9^a, mounted on the same shaft, and each section of each clamp is provided with a hub or bearing sleeve 10, fitting over the threaded outer end of the shaft. The inner sections 9^a of the clamps are moved toward the outer sections by means of nuts 11, and the outer sections 9 are moved toward the inner sections by handle nuts 12.

Each clamping member is shaped to engage the edge of the rim 13 to be contracted. It will be noted that each clamping section consists of a plain horizontal portion and an arc-shaped portion integral therewith, the bearing sleeve or hub 10 being below the horizontal portion, and the arc-shaped portion being at the outer end of the plain portion.

The horizontal portions extending beyond the inner ends of the sleeves 10 may act as stops to prevent crushing of the rim between the clamping members. The rod 4 is arranged at the upper end of an arm 14, whose lower end is pivoted as indicated at 15 to a lever 16, which is pivoted to a post 17, extending laterally from the table at the outer side of the said rod 4.

It will be evident that when the outer end of the lever 16 is depressed, the rod 4 and the clamping member connected therewith will also be depressed. A lever 18 is pivoted at its lower end to a block 19 mounted to slide on a rod 20, which is supported in openings in angular lugs 21 of plates 22, secured to the base. The plates 22 are in alinement, and are arranged with the openings of the lugs 21 in register. The rod 20 is held in the lugs, and the block 19 is arranged at the center of the rod.

Coil springs 23 encircle the rod on opposite sides of the block between the block and the bearing lugs 21, and the springs act normally to hold the block at a point half way between the bearing lugs. The lever is held in adjusted position by pins 24 on an arc-shaped bar or sector 25, secured to the base 100 above the rod 20. The pins are spaced apart from each other at equal distances and far enough to permit the lever to engage between them.

It will be noted from an inspection of Fig. 3 that the lower end of the lever 18 is forked, and the arms 26 of the fork engage opposite sides of the block 19, and are piv-

oted thereto by means of oppositely extending journal pins 27 on the block.

A link 28 connects the lever 18 with the arm 14 near its upper end, and it will be evident that when the upper end of the lever is swung, the rod 4 and its clamping member will be moved toward or from the clamping member of the rod 3, depending upon the direction of the movement of the lever.

The lever 18 may yield however, at its lower end, compressing one or the other of the springs 23. The arm 14 is reinforced at its upper end by means of a bar 29. The said bar has a bearing 30 at its upper end which engages the shaft 4, and the lower end of the bar is offset outwardly into contact with the inner face of the arm 14, and is secured thereto as indicated at 31.

The body of the bar 29 is spaced apart inwardly from the arm 14 to receive the adjacent end of the link 28 between the bar and the arm, and the pivotal connection 32 of the link passes through both arm and bar. The post 17 is braced at its outer end by an inclined brace 33. The lower end of this brace engages the post at its outer end, and the upper end of the brace is offset inwardly to a connection with the base.

A bar 34 is arranged between the rod 4^a and the base. One end of the bar 34 has an opening for receiving the rod 4^a, and the bar engages the rod just outside a nut 35 on the rod. The opposite end of the bar 34 is offset inwardly to a connection with the base at the upper end of the brace 33, before mentioned.

The operation of the remover is as follows:—When it is desired to place a tire for instance, the rim 13 is arranged as shown in Fig. 1. The sections of each clamp are separated by turning the handle nuts 12, until the rim will engage between the sections of the clamps. The sections are then moved toward each other to clamp the rim between the sections of the respective clamps. At this time the lever 18 is at the position shown in Fig. 1, being held in such position by the pins 24 of the sector 25. With the rim so clamped the outer end of the lever 16 is depressed.

This movement of the lever draws the arm 14 downward and the rod 4 which supports the adjacent clamping mechanism is moved, therewith drawing one end of the split rim downward as shown, while the other end is held in clamped position by the clamps on the rods 3 and 4^a. The operator now releases the lever 18 from the pins 24 and swings it in the direction of the arrow in Fig. 1. The link 28 is drawn with the lever 18, and the arm 14 is swung in a direction to move the clamp on the rod 4 toward the clamp on the rod 3, and the split ends of the rim are overlapped, as shown in Fig. 2, that end con-

nected with the clamp on the rod 4 moving with respect to that end in the clamp on the rod 3.

The rim is now contracted, and in position to receive the tire which may be slipped over the sections 9 of the clamps. It will be noted that the arc-shaped portions of these sections are spaced apart far enough to permit the seating of the tire. After the tire has been placed, the lever 18 is released from the pins 24, and permitted to swing into the position of Fig. 1. The lever 16 is then released, and the split ends of the rim resume their normal position. To remove the tire the operation is precisely the same as above specified.

The rim lock 36 prevents excess movement of the movable end of the rim beyond normal position. In placing the tire the movable end of the rim may be forced into the normal position by moving the lever 16 upward after the lever 18 has been released as above specified. One man can easily remove or replace a tire with the above mechanism.

The provision of two clamps for the fixed end of the rim prevents distortion of the said end, since the two clamps grip the said ends in spaced relation.

It will be understood that the rod 20 may be mounted to move in the lugs 21 if desired, the block 19 being rigid with the rods.

I claim:—

1. A device of the character specified, comprising a base, a pair of clamps, one of which is rigidly connected with the base, an arm connected at its upper end with the other clamp, a lever pivoted to the base and connected to the arm intermediate the ends of the lever for moving the clamp downward, a second lever, a connection between the said lever and the arm for swinging the clamp toward the first-named clamp, said second lever having a pivotal mounting, and the pivotal mounting being mounted to yield with respect to the base.

2. A device of the character specified, comprising a base, a pair of clamps, one of which is rigidly connected with the base, an arm connected at its upper end with the other clamp, a lever pivoted to the base and connected to the arm intermediate the ends of the lever for moving the clamp downward, a second lever, and a connection between the said lever and the arm for swinging the clamp toward the first-named clamp.

3. In a machine for contracting and expanding a split rim, means for securing the rim upon one side of the split, a clamp engaging the rim upon the opposite side of the split, means for moving the clamp inward to disalign the ends of the rim, and other means for moving the clamp toward the rim securing means to contract the rim.

4. In a machine for contracting and ex-

anding a split rim, fixed clamping means for engaging the rim upon one side of the split, a clamp engaging the rim upon the opposite side of the split, a lever for moving the clamp to cause one end of the

rim engaged thereby to slide beneath the end of the rim held by the fixed clamping means.
